Primary Examiner — Marc Carlson(74) *Attorney, Agent, or Firm* — Fish & Richardson P.C.(57) **ABSTRACT**

A vacuum cleaner includes a suction nozzle including a housing that defines an inlet, a first shaft disposed at a side of the housing, a driver configured to rotate the first shaft, a rotating brush that extends along an axis and is configured to, based on rotation of the first shaft, rotate about the axis to thereby move dust on a surface to toward the inlet, a detachable cover configured to rotatably support a first end of the rotating brush, and a second shaft disposed at a second end of the rotating brush and configured to engage with the first shaft to rotate the rotating brush. The first shaft and the second shaft are configured to contact each other and to define first contact surfaces that have a spiral shape about the axis and that are configured to transfer rotational force from the first shaft to the second shaft.

VACUUM CLEANER

CROSS-REFERENCE TO RELATED APPLICATION

This present application claims the benefit of priority to Korean Patent Application No. 10-2019-0159188, entitled "VACUUM CLEANER," filed on Dec. 3, 2019, the entire disclosure of which is incorporated herein by reference.

TECHNICAL FIELD

The present disclosure relates to a vacuum cleaner and, more particularly, to a vacuum cleaner configured to suction dust with a rotating brush from a floor.

BACKGROUND

Vacuum cleaners may have various types of brushes.

For example, a stiff plastic brush may be used for carpets. In some cases, a floor brush made of soft flannel may be used for cleaning a smooth floor.

In some cases, the floor brush made of soft flannel may be used to avoid scratching on floors that could be caused by a stiff brush. In some cases, as the flannel brush is rotated for cleaning, fine dust on the floor may be lifted into the air and suctioned by the vacuum cleaner.

In some examples, a vacuum cleaner may include a main body and a suction nozzle. The suction nozzle may include a housing, a rotating cleaning unit, a driver, and a rotating support unit.

In some cases, the rotating cleaning unit may be moved within a tolerance in an axial direction between the driver and the rotating support unit.

The rotating cleaning unit may include multiple bristles. In some cases, the rotating cleaning unit may rotate and generate friction with the floor. The floor may be made of a synthetic resin or wood.

In some examples, a user may clean the floor by moving the suction nozzle in front and rear directions. In some cases, when the direction of the suction nozzle is changed, the suction nozzle may move in left and right directions. In some cases, when the direction of the suction nozzle is changed, the suction nozzle may move in front and rear directions and in an inclined direction.

In some examples, a reaction force and a friction force of the floor may act on the rotating cleaning unit. For instance, when the direction of the suction nozzle is changed, the reaction force and the friction force of the floor may be applied to the rotating cleaning unit in the axial direction thereof.

In some cases, the axial-directional movement of the rotating cleaning unit may cause noise on contact surfaces between the rotating cleaning unit and the rotating support unit and between the first side surface cover and the second side surface cover and the chamber.

In some cases, the axial-directional movement of the rotating cleaning unit may cause damage to the coupling structure of the first side surface cover, the second side surface cover, and the chamber. When the coupling structure of the first side surface cover, the second side surface cover, and the chamber is damaged, the rotating cleaning unit may vibrate while cleaning the floor. This causes power loss of the motor. As a result, the rotating cleaning unit may not properly lift the dust on the floor into the air, which could lead to a weakening of the cleaning function.

2

In some cases, the driver may be coupled to the rotating cleaning unit by a fixing member in the rotating cleaning unit and may be difficult for the user to disassemble and reassemble the driver and the rotating cleaning unit.

5

SUMMARY

The present disclosure describes a vacuum cleaner that may restrict axial-directional movement of a rotating brush caused by the reaction force and the friction force of a floor.

The present disclosure also describes a vacuum cleaner that may restrict axial-directional movement and radial-directional movement of the rotating brush.

The present disclosure further describes a vacuum cleaner including a driver and a brush module that may be disassembled and reassembled.

According to one aspect of the subject matter described in this application, a vacuum cleaner includes a main body configured to generate a differential air pressure with respect

20 to an outside of the vacuum cleaner, and a suction nozzle configured to suction dust from the outside based on the differential air pressure. The suction nozzle includes a housing that defines an inlet configured to receive the dust, a first shaft disposed at a side of the housing, a driver disposed at the housing and configured to rotate the first shaft, a rotating brush that extends along an axis and is configured to, based on rotation of the first shaft, rotate about the axis to thereby move the dust on a surface to toward the inlet, a detachable cover configured to rotatably support a first end of the rotating brush, and a second shaft disposed at a second end of the rotating brush and configured to engage with the first shaft to rotate the rotating brush. The first shaft and the second shaft are configured to come into contact with each other and to define a plurality of first 30 contact surfaces having a spiral shape about the axis of the rotating brush, the first contact surfaces being configured to transfer a rotational force from the first shaft to the second shaft.

35 Implementations according to this aspect may include one or more of the following features. For example, the first shaft and the second shaft may be configured to further define a plurality of second contact surfaces, the second contact surfaces extending in parallel to the axis of the rotating brush and being configured to transfer a rotational inertia of the rotating brush to the first shaft. In some examples, the first contact surfaces are axisymmetric with respect to the axis of the rotating brush. In some examples, the first contact surfaces may be curved along a rotational direction of the first shaft and extend in a direction from the second end of the rotating brush toward the first end of the rotating brush.

40 In some implementations, the first shaft and the second shaft may be configured to contact each other at the first contact surfaces and slide with respect to each other, and the first shaft may be configured to push the second shaft in an axial direction of the rotating brush through the first contact

45 surfaces. In some examples, the first shaft and the second shaft may be configured to further define a plurality of second contact surfaces that extend in parallel to the axis of the rotating brush and are configured to transfer a rotational inertia of the rotating brush to the first shaft. The first shaft and the second shaft may be configured to, based on the first shaft pushing the second shaft in the axial direction of the rotating brush, be separated from the second contact surfaces.

50 In some implementations, the first shaft and the second shaft may be configured to contact each other at the first contact surfaces and slide with respect to each other, and the first shaft may be configured to push the second shaft in an axial direction of the rotating brush through the first contact

55 surfaces. In some examples, the first shaft and the second shaft may be configured to further define a plurality of second contact surfaces that extend in parallel to the axis of the rotating brush and are configured to transfer a rotational inertia of the rotating brush to the first shaft. The first shaft and the second shaft may be configured to, based on the first shaft pushing the second shaft in the axial direction of the rotating brush, be separated from the second contact surfaces.

60 In some implementations, the first shaft and the second shaft may be configured to contact each other at the first contact surfaces and slide with respect to each other, and the first shaft may be configured to push the second shaft in an axial direction of the rotating brush through the first contact

65 surfaces. In some examples, the first shaft and the second shaft may be configured to further define a plurality of second contact surfaces that extend in parallel to the axis of the rotating brush and are configured to transfer a rotational inertia of the rotating brush to the first shaft. The first shaft and the second shaft may be configured to, based on the first shaft pushing the second shaft in the axial direction of the rotating brush, be separated from the second contact surfaces.

brush toward the first end of the rotating brush. In some examples, a surface area of the first contact surfaces may decrease as the first shaft extends in a direction from the second end of the rotating brush toward the first end of the rotating brush.

In some implementations, the first shaft may include a plurality of first transfer portions configured to insert into the second end of the rotating brush, and the second shaft may include a plurality of second transfer portions that may be configured to come into contact with the first transfer portions to thereby define the plurality of first contact surfaces. In some examples, the housing may define a side hole configured to receive the first shaft. In some examples, the second shaft may be disposed in a through-hole of the rotating brush and defines an aperture that is configured to receive the first shaft passing through the side hole of the housing.

In some implementations, the vacuum cleaner may further include a third shaft inserted into the first end of the rotating brush, and the detachable cover may be configured to cover the third shaft.

According to another aspect, a vacuum cleaner includes a main body configured to generate a differential air pressure with respect to an outside of the vacuum cleaner, and a suction nozzle configured to suction dust from the outside based on the differential air pressure. The suction nozzle includes a housing that defines an inlet configured to receive the dust, a first shaft that is disposed at a side of the housing and includes a plurality of first surfaces, a driver disposed at the housing and configured to rotate the first shaft, a rotating brush that extends along an axis and is configured to, based on rotation of the first shaft, rotate about the axis to thereby move the dust on a surface toward the inlet, a detachable cover configured to rotatably support a first end of the rotating brush, and a second shaft disposed at a second end of the rotating brush and configured to engage with the first shaft to rotate the rotating brush. The second shaft includes a plurality of second surfaces configured to come into contact with the first surfaces to thereby define a plurality of first contact surfaces. The plurality of first contact surfaces have a spiral shape about the axis of the rotating brush and are configured to transfer a rotational force from the first shaft to the second shaft.

Implementations according to this aspect may include one or more of the following features. For example, the first shaft may further include a plurality of third surfaces, and the second shaft may further include a plurality of fourth surfaces that are configured to come into contact with the third surfaces to thereby define a plurality of second contact surfaces. The second contact surfaces extend in parallel to the axis of the rotating brush and being configured to transfer a rotational inertia of the rotating brush to the first shaft.

In some implementations, the first contact surfaces may be curved along a rotational direction of the first shaft and extend in a direction from the second end of the rotating brush to the first end of the rotating brush. One of the first surfaces and one of the second surfaces may be configured to slide with respect to each other based on the rotational force being applied from the first shaft to the second shaft. The first shaft may be configured to push the second shaft in an axial direction of the rotating brush.

In some implementations, the first shaft may include a plurality of third surfaces, and the second shaft may include a plurality of fourth surfaces that are configured to come into contact with the third surfaces to thereby define a plurality of second contact surfaces. The second contact surfaces may extend in parallel to the axis of the rotating brush and be

configured to transfer a rotational inertia of the rotating brush to the first shaft. One of the third surfaces and one of the fourth surfaces may be configured to, based on the first shaft pushing the second shaft in an axial direction of the rotating brush, be spaced apart from each other.

In some implementations, the first shaft may include a plurality of first transfer portions that define the first surfaces, respectively, where the first transfer portions are configured to insert into the second end of the rotating brush. The second shaft may include a plurality of second transfer portions that define the second surfaces, respectively, where the second transfer portions are configured to come into contact with the first transfer portions to thereby define the plurality of first contact surfaces.

In some implementations, the housing may define a side hole configured to receive the first shaft. In some examples, the second shaft may be disposed in a through-hole of the rotating brush and define an aperture that is configured to receive the first shaft passing through the side hole of the housing.

In some implementations, the first shaft and the second shaft may come into contact with each other on a plurality of first contact surfaces, and the first contact surfaces may have a spiral shape around the axis of the rotating brush. Accordingly, the rotational force of the first shaft may be used to rotate the rotating brush and to push the rotating brush in the axial direction thereof. Thus, even if a reaction force and a friction force of the floor act on the rotating brush, axial-directional movement of the rotating brush may be minimized.

In some implementations, the first shaft and the second shaft may come into contact with each other on a plurality of second contact surfaces, and the second contact surfaces may form a surface which is parallel to the axis of the rotating brush. In some examples, when an external force is applied to the rotating brush in the radial direction, the first shaft and the second shaft may come into close contact with each other on the second contact surfaces, such that radial-directional movement of the rotating brush may be blocked.

In some implementations, the first contact surfaces may have a spiral shape around the axis of the rotating brush as a center, and the second contact surfaces may be parallel to the axis of the rotating brush. Accordingly, when the brush module is moved in the direction of the rotational axis of the rotating brush, the second shaft may engage with or disengage from the first shaft.

BRIEF DESCRIPTION OF THE DRAWINGS

FIG. 1 is a perspective view of an example of a vacuum cleaner.

FIG. 2 is a perspective view of an example of a suction nozzle of the vacuum cleaner of FIG. 1 seen from above.

FIG. 3 is a perspective view of the suction nozzle of the vacuum cleaner of FIG. 1 seen from below.

FIG. 15 is a cross-sectional view of the suction nozzle of FIG. 14 along the line from A to A'.

FIG. 16 is a perspective view of an example of a brush module of FIG. 4.

FIG. 17 is an exploded perspective view of the brush module of FIG. 16.

FIG. 18 is a perspective view of the suction module of FIG. 2 with the brush module separated.

FIG. 19 is a perspective view of the suction module of FIG. 2 with the housing and the detachable cover coupled.

FIG. 20 is a perspective view of the suction module of FIG. 2 with the housing and the detachable cover decoupled.

FIG. 21 is a perspective view of the suction module of FIG. 18 without the rotating brush.

FIG. 22 is a perspective view of the suction module of FIG. 21 and an example of a pressing button separated from the suction module.

FIG. 23 is a perspective view of the detachable cover of FIG. 21.

FIG. 24 is a side view of the suction nozzle of FIG. 20.

FIG. 25 is a side view of the suction nozzle of FIG. 19 with the pressing button pressed.

FIG. 26 is a side view of the suction nozzle of FIG. 19.

FIG. 27 is a perspective view of the brush module and the driver of the suction module of FIG. 19.

FIG. 28 is a side view of the driver of FIG. 27.

FIG. 29 is a perspective view of a first shaft of FIG. 28.

FIG. 30 is a side view of the brush module of FIG. 27.

FIG. 31 is a partial perspective view of an example of a second shaft of FIG. 30.

FIG. 32 is a cross-sectional view of the suction module of FIG. 19.

FIG. 33 is a cross-sectional view of the suction module of FIG. 32 along the line from B to B'.

FIG. 34 is a cross-sectional view of the suction module of FIG. 32 along the line from C to C'.

FIG. 35 is a cross-sectional view of the suction module of FIG. 32 along the line from D to D'.

FIG. 36 is a drawing illustrating an example of a force acting on a first contact surface.

FIG. 37 is a drawing illustrating an example of a force acting on a second surface.

FIG. 38 is a drawing illustrating an example of a force acting on a second contact surface.

DETAILED DESCRIPTION

Advantages and features of the present disclosure and methods for achieving them will become apparent from the descriptions of aspects herein below with reference to the accompanying drawings. However, the present disclosure is not limited to the aspects disclosed herein but may be

implemented in various different forms. The aspects are provided to make the description of the present disclosure thorough and to fully convey the scope of the present disclosure to those skilled in the art. It is to be noted that the scope of the present disclosure is defined only by the claims.

The shapes, sizes, ratios, angles, the number of elements given in the drawings are merely exemplary, and thus, the present disclosure is not limited to the illustrated details. Like reference numerals designate like elements throughout the specification.

Hereinafter, one or more implementations of the present disclosure will be described in detail referring to the attached drawings.

FIG. 1 is a perspective view of an example of a vacuum cleaner 1.

In some implementations, as illustrated in FIG. 1, the vacuum cleaner 1 may include a main body 20 and a suction nozzle 10.

The suction nozzle 10 may be connected to the main body 20 through an extension pipe 30. The suction nozzle 10 may be directly connected to the main body 20. A user may grip a handle 21 formed in the main body 20 and move the suction nozzle 10 back and forth on a floor.

The main body 20 may generate a difference in air pressure. Inside the main body 20, an air blower may be provided. When the air blower generates a difference in air pressure, dust and debris on the floor may be moved into the main body 20 through an inlet 111 of the suction nozzle 10 and the extension pipe 30.

Inside the main body 20, a centrifugal dust collector may be provided. The dust and debris may be received in a dust box 22.

FIG. 2 is a perspective view of the suction nozzle 10 of the vacuum cleaner 1 of FIG. 1 seen from above. FIG. 3 is a perspective view of the suction nozzle 10 of the vacuum cleaner 1 of FIG. 1 seen from below. FIG. 4 is an exploded perspective view of the suction nozzle 10 of FIG. 2.

The suction nozzle 10 may suction dust from an outside of the vacuum cleaner 1 by using a difference in air pressure. For example, the main body 20 may generate a differential air pressure with respect to an outside of the vacuum cleaner 1, and the suction nozzle 10 may suction dust on a floor. The suction nozzle 10 may include a housing 100, a driver 200, a brush module 300, and a connector 400.

Hereinafter, for easy understanding of the present disclosure, a side of the suction nozzle 10 where a rotating brush 310 is positioned will be referred to as the front of the suction nozzle 10, and a side of the suction nozzle 10 where the connector 400 is positioned will be referred to as the rear or back of the suction nozzle 10.

The suction nozzle 10 may be assembled in the following order. Firstly, the connector 400 may be assembled. Secondly, a mounting housing 130 may be assembled with the connector 400.

The mounting housing 130 may be rotatably mounted in the connector 400. Then, the driver 200 may be coupled to one side of a main housing 110.

Thereafter, the mounting housing 130 may be coupled to an upper portion of the main housing 110. Next, a lower housing 120 may be coupled to a lower portion of the main housing 110. Then, a support housing 140 may be coupled to a lower portion of the main housing 110.

Thereafter, a pressing button 141 may be mounted in the support housing 140. Next, a side surface cover 150 may be coupled to one side of the main housing 110.

In some implementations, a first shaft 232D may be inserted into a second shaft 313 of a rotating brush 310, and

a detachable cover 320 may be detachably coupled to the other side of the main housing 110. Then, the assembly of the suction nozzle 10 may be completed. For example, the first shaft 232D may be inserted into a through-hole of the rotating brush 310, and the second shaft 313 may define an aperture that receives the first shaft 232D.

FIG. 5 is a cross-sectional view of the suction nozzle 10 of FIG. 2.

As illustrated in FIGS. 4 and 5, the housing 100 may guide dust and debris on the floor to a passage 401 of the connector 400.

The housing 100 may include a main housing 110, a lower housing 120, a mounting housing 130, and a support housing 140.

The main housing 110 may form an inlet 111 through which dust moves to the main body 20. The inlet 111 may be formed behind the main housing 110. The inlet 111 may be formed in a cylindrical shape. A rotating brush 310 may be mounted in front of the main housing 110.

A front of the main housing 110 (hereinafter referred to as a "front portion 110A") may cover an upper portion of the rotating brush 310. The front portion 110A may form a wall that extends in a circumferential direction of a rotational axis of the rotating brush 310. The front portion 110A may be spaced apart from the upper portion of the rotating brush 310 by a certain distance.

The rotating brush 310 may be rotated by the driver 200. The rotating brush 310 may push dust and debris on the floor to behind the rotating brush 310. The dust and debris pushed to behind the rotating brush 310 may easily enter the inlet 111. The main housing 110, positioned between the rotating brush 310 and the inlet 111, may cover the surface of the floor.

Between the rotating brush 310 and the inlet 111, the housing 100 may define a space (hereinafter referred to as a "suction space 101") between the housing 100 and the floor. Excluding a gap formed between the housing 100 and the floor, the suction space 101 may be isolated from outside. The dust and debris in the suction space 101 may enter the passage 401 through the inlet 111.

As illustrated in FIGS. 4 and 5, the lower housing 120, with the main housing 110, may form the suction space 101. The lower housing 120 may include a first lower housing 121 and a second lower housing 122.

The first lower housing 121 and the second lower housing 122, positioned between the rotating brush 310 and the inlet 111, may form a wall which guides the dust and debris in the suction space 101 towards the inlet 111.

The lower housing 120, with the support housing 140, may be coupled to a lower portion of the main housing 110 by a bolt. In the main housing 110, a fastening portion (N) to which a bolt is screw-coupled may be formed. In the first lower housing 121, the second lower housing 122, and the support housing 140, an insertion portion (T) into which a bolt is inserted may be formed.

The first lower housing 121 may include a first wall surface 121A and a second wall surface 121B.

An upper portion of the first wall surface 121A may be disposed in close contact with the front portion 110A. A front surface of the first wall surface 121A may come into contact with the brush member 312. When the brush member 312 rotates, dust and debris adhering to the brush member 312 may bump against a lower portion of the first wall surface 121A to thereby come off the brush member 312.

The second wall surface 121B and the second lower housing 122, positioned between left and right sides of the

inlet 111 and the floor, may form a wall which guides dust and debris in the suction space 101 towards the inlet 111. A pair of first wheels (W1) may be mounted in the second lower housing 122.

FIG. 6 is an exploded perspective view of the mounting housing 130 and the connector 400 of the suction nozzle 10 of FIG. 4 seen from above. FIG. 7 is an exploded perspective view of the mounting housing 130 and the connector 400 of the suction nozzle 10 of FIG. 4 seen from below.

As illustrated in FIGS. 6 and 7, the mounting housing 130 may include a cover portion 131, a mounting portion 132, and an interposition portion 133.

The cover portion 131 may be a portion that is mounted in an upper portion of the main housing 110. In any one of the cover portion 131 or the main housing 110, a protrusion (P) may be formed. In the other one of the cover portion 131 or the main housing 110, a hole (H) may be formed. As the protrusion (P) is inserted into the hole (H), the cover portion 131 may be mounted in the upper portion of the main housing 110.

The mounting portion 132 may be a portion that surrounds the inlet 111 and a coupling part 440. The mounting portion 132 may be formed in a ring shape.

The interposition portion 133 may protrude from an inner surface of the mounting portion 132. The interposition portion 133 may be a portion that is rotatably mounted in the connector 400. The interposition portion 133 may protrude from the inner surface of the mounting portion 132 along a circumferential direction of the mounting portion 132.

As illustrated in FIGS. 4 and 5, the support housing 140 may support lower portions of the suction nozzle 10 and the connector 400.

In the support housing 140, a second wheel (W2) may be mounted. The second wheel (W2) may, together with the pair of first wheels (W1), rotate and roll on the floor.

The pair of first wheels (W1) and the second wheel (W2) may provide a rolling motion to the suction nozzle 10 and the connector 400. A pressing button 141 may be mounted in the support housing 140.

The connector 400 may enable relative rotation of the main body 20 and the suction nozzle 10. In addition, the connector 400 may form therein the passage 401 through which dust moves into the main body 20.

As illustrated in FIGS. 6 and 7, the connector 400 may include an insertion portion 410, a first connection portion 420, a second connection portion 430, a coupling part 440, and an elastic pipe 450.

Each of the first connection portion 420 and the second connection portion 430 may be formed in a pipe shape. The first connection portion 420 and the second connection portion 430 may be rotatably coupled to each other.

In some implementations, in any one of the first connection portion 420 or the second connection portion 430, a pair of protrusions may be formed. In addition, in the other one of the first connection portion 420 or the second connection portion 430, a pair of grooves may be formed.

The pair of protrusions may be formed on an outer surface of the second connection portion 430 at both sides thereof. The pair of grooves may be formed on an inner surface of the first connection portion 420 at both sides thereof. The protrusions may be inserted into the grooves. The second connection portion 430 may be rotated about the protrusions inserted into the grooves. Reference sign "X" in FIG. 6 indicates an extension line of the rotational axis formed by the protrusions.

As illustrated in FIG. 5, in an upper portion of the second connection portion 430, a release button 431 may be formed.

The release button 431 may be connected to an engaging portion 432. In an upper portion of the second connection portion 430, a hole may be formed. The engaging portion 432 may protrude into the second connection portion 430 through the hole.

In the extension pipe 30, a hole into which the engaging portion 432 is inserted may be formed. Movement of the extension pipe 30 may be blocked by the engaging portion 432.

When a user presses the release button 431, the engaging portion 432 may move upward and be released from the hole of the extension pipe 30. Accordingly, the second connection portion 430 and the extension pipe 30 may be separated from each other. When an external force applied to the release button 431 is removed, the release button 431 may move upward again by its own elasticity. When the external force applied to the release button 431 is removed, the engaging portion 432 may move downward again.

As illustrated in FIG. 5, the elastic pipe 450 may form the passage 401 between the inlet 111 and the second connection portion 430. The elastic pipe 450 may include an elastic tube 451 and a coil spring 452.

The elastic tube 451 may form therein the passage 401. The elastic tube 451 may be formed in a cylindrical shape. The elastic tube 451 may be made of a soft resin. Accordingly, the elastic tube 451 may be elastically deformed when the first connection portion 420 and the second connection portion 430 are relatively rotated, and when the mounting portion 132 and the first connection portion 420 are relatively rotated.

The coil spring 452 may be attached to an inner surface or an outer surface of the elastic tube 451. The coil spring 452 may maintain the cylindrical shape of the elastic tube 451.

In a compressed state, the coil spring 452 may be mounted between the inlet 111 and the second connection portion 430. In each of the inlet 111 and the second connection portion 430, a raised portion may be formed, and both end portions of the coil spring 452 may be caught by the raised portions of the inlet 111 and the second connection portion 430.

A distance between the raised portions of the inlet 111 and the second connection portion 430 may change when the first connection portion 420 and the second connection portion 430 are relatively rotated, and when the mounting portion 132 and the first connection portion 420 are relatively rotated.

The elastic tube 451 may be maintained to be in close contact with the raised portions of the inlet 111 and the second connection portion 430 by the elasticity of the coil spring 452 while the first connection portion 420 and the second connection portion 430 are relatively rotated, and while the mounting portion 132 and the first connection portion 420 are relatively rotated.

FIG. 8 is a perspective view of an assembled state of the mounting housing 130 and the connector 400 of the suction nozzle 10 of FIG. 4. FIG. 9 is a perspective view of an assembled state of the main housing 110, the mounting housing 130, and the connector 400 of the suction nozzle 10 of FIG. 4.

FIG. 10 is a partial cross-sectional view of an assembled state of the main housing 110, the mounting housing 130, and the connector 400 of the suction nozzle 10 of FIG. 9.

The insertion portion 410 may be formed in a pipe shape having a diameter smaller than a diameter of the first connection portion 420. The insertion portion 410 may be coupled inside the first connection portion 420 by a bolt. In the first connection portion 420, a fastening portion (N) to

which a bolt is screw-coupled may be formed. In the insertion portion 410, an insertion portion (T) into which a bolt is inserted may be formed.

The insertion portion 410 may protrude forward from inside the first connection portion 420. A front surface of the first connection portion 420 may be formed in a ring shape surrounding the insertion portion 410.

The coupling part 440 may connect the mounting housing 130 and the connector 400 to each other in such a manner that the mounting housing 130 and the connector 400 rotate about the insertion portion 410. The coupling part 440 may restrain forward and backward movement of the mounting portion 132 and the interposition portion 133 from the first connection portion 420. In other words, the coupling part 440 may restrain forward and backward movement of the insertion portion 410 and the first connection portion 420 from the interposition portion 133.

After the insertion portion 410 is inserted into the mounting portion 132, the coupling part 440 may be mounted in an outer surface of the insertion portion 410. Thereafter, the elastic pipe 450 may be inserted into the insertion portion 410. Then, the cover portion 131 may be mounted in an upper portion of the main housing 110.

When the cover portion 131 is mounted in the upper portion of the main housing 110, the insertion portion 410 may be inserted into the inlet 111. The first connection portion 420 may be spaced apart from the inlet 111 in the direction of the passage 401. The "direction of the passage 401" should be understood as the "direction of the central axis of the insertion portion 410."

As illustrated in FIGS. 7 and 10, the coupling part 440 may include a pipe portion 441, a protrusion portion 442, and a spacing protrusion portion 443.

The pipe portion 441 may be formed in a cylindrical shape. When the coupling part 440 is mounted in the outer surface of the insertion portion 410, an inner surface of the pipe portion 441 may surround the outer surface of the insertion portion 410. Thereafter, when the cover portion 131 is mounted in the upper portion of the main housing 110, an inner surface of the inlet 111 may surround an outer surface of the pipe portion 441.

The spacing protrusion portion 443 may protrude from the outer surface of the pipe portion 441 in a circumferential direction. The pipe portion 441 may be spaced apart from the inner surface of the inlet 111 by the spacing protrusion portion 443. The spacing protrusion portion 443 may also be spaced apart from the inner surface of the inlet 111.

When an external force is applied to the connector 400, the spacing protrusion portion 443 may come into contact with the inner surface of the inlet 111. A contact surface between the spacing protrusion portion 443 and the inlet 111 may be relatively small compared to the outer surface of the pipe portion 441. Accordingly, even when the spacing protrusion portion 443 comes into contact with the inner surface of the inlet 111, relative rotation of the mounting housing 130 and the first connection portion 420 may be possible.

In some related art, when the second connection member receives an external force from the first connection member, the second connection member may be deformed in the opposite direction to the first connection member, that is, in the outer direction. For this reason, the connection members, which are rotatably coupled, may be easily become decoupled by an external force applied to the first connection member.

In some implementations, when the coupling part 440 is mounted in the outer surface of the insertion portion 410, the

11

inner surface of the pipe portion 441 may surround the outer surface of the insertion portion 410. Thereafter, when the cover portion 131 is mounted in the upper portion of the main housing 110, the inner surface of the inlet 111 may surround the outer surface of the pipe portion 441.

Accordingly, when the pipe portion 441, which has received the external force from the insertion portion 410, is deformed in the opposite direction to the insertion portion 410, that is, in the outer direction, the inner surface of the inlet 111 may serve as a boundary surface for helping to prevent deformation of the pipe portion 441.

That is, even when the insertion portion 410 is deformed by the external force applied to the connector 400, and thus the external force is transferred to the pipe portion 441, the inlet 111 may have a rigidity to avoid deformation of the pipe portion 441.

Accordingly, the inlet 111 may help to prevent relative deformation of the insertion portion 410 and the coupling part 440. As a result, in some implementations, even when a strong external force acts on the connector 400, the mounting portion 132 and the first connection portion 420 may not become decoupled from each other.

As illustrated in FIGS. 7 and 10, in any one of the insertion portion 410 or the pipe portion 441, a catch hole 411 may be formed. In the other one of the insertion portion 410 or the pipe portion 441, a catch portion 441A may be formed. For example, the catch portion 441A may be formed in the pipe portion 441, and the catch hole 411 may be formed in the insertion portion 410.

The catch portion 441A may protrude inward from an inner surface of the pipe portion 441. The protruding height of the catch portion 441A inside the pipe portion 441 may become smaller towards the backward direction.

When the insertion portion 410 is inserted into the coupling part 440, the catch portion 441A may be bent outwards by the outer surface of the insertion portion 410. When the catch portion 441A is inserted into the catch hole 411, the coupling part 440 may be mounted in the outer surface of the insertion portion 410.

The catch portion 441A may form a surface perpendicular to the direction of the passage 401. Accordingly, even when the coupling part 440 is pulled in the forward direction, a state in which the catch portion 441A is caught in the catch hole 411 may be maintained.

If the connection members are rotatably connected to each other are coupled to each other by forceful insertion, when the connection members are decoupled from each other for the purpose of repairing and the like, the connection members may easily become worn or broken at areas that are coupled by the forceful insertion.

In some implementations, when the catch portion 441A is pushed outwards from inside the insertion portion 410, the catch portion 441A that is caught in the catch hole 411 may be easily released from the catch hole 411.

When the coupling part 440 is pulled forwards while the catch portion 441A is being pushed outwards from inside the insertion portion 410, the insertion portion 410 and the coupling part 440 may be easily decoupled from each other. Accordingly, the present disclosure has an advantage in that the mounting housing 130 and the first connection portion 420 may be easily decoupled without any abrasion or damage.

As illustrated in FIGS. 7 and 10, the protrusion portion 442 may protrude from the outer surface of the pipe portion 441 in the circumferential direction. The protrusion portion 442 may form a first boundary surface 442A.

12

The first connection portion 420 may form a second boundary surface 421. The second boundary surface 421 may be spaced apart from the first boundary surface 442A in the direction of the passage 401.

When the coupling part 440 is mounted in the outer surface of the insertion portion 410, the interposition portion 133 may be interposed between the first boundary surface 442A and the second boundary surface 421. The first boundary surface 442A and the second boundary surface 421 may 10 block movement of the interposition portion 133 in the direction of the passage 401.

The first boundary surface 442A and the second boundary surface 421 may form a ring shape around a central axis of the insertion portion 410. The first boundary surface 442A and the second boundary surface 421 may face each other in a direction of the central axis of the insertion portion 410. Accordingly, the mounting housing 130 may be mounted in the connector 400 to rotate about the central axis of the insertion portion 410.

20 The protrusion portion 442 may form a third boundary surface 442B. The third boundary surface 442B may be formed on an outer surface of the protrusion portion 442 in a circumferential direction. The third boundary surface 442B may have a constant radius along the circumferential direction of the central axis of the insertion portion 410. The first boundary surface 442A and the third boundary surface 442B may form an angle of about 90 degrees.

25 The interposition portion 133 may form a fourth boundary surface 133A. The mounting portion 132 may form a circular ring shape. The interposition portion 133 may form the fourth boundary surface 133A along a circumferential direction of a central axis of the mounting portion 132. The second boundary surface 421 and the fourth boundary surface 133A may form an angle of about 90 degrees.

30 The third boundary surface 442B and the fourth boundary surface 133A may face each other in a radial direction of the pipe portion 441. The third boundary surface 442B and the fourth boundary surface 133A may come into close contact with each other when the insertion portion 410 moves in a radial direction. Accordingly, the third boundary surface 442B and the fourth boundary surface 133A may block radial directional movement of the insertion portion 410 with respect to the mounting portion 132.

35 The protrusion portion 442 may form a fifth boundary surface 442C. The fifth boundary surface 442C may be formed on an outer surface of the protrusion portion 442 in the circumferential direction.

The fifth boundary surface 442C may have a constant radius along the circumferential direction of the central axis of the insertion portion 410. The third boundary surface 442B and the fifth boundary surface 442C may form a stepped portion. The first boundary surface 442A and the fifth boundary surface 442C may form an angle of about 90 degrees.

50 55 On an inner surface of the mounting portion 132, a sixth boundary surface 133B may be formed. The inner surface of the mounting portion 132 may form a circular ring shape. The mounting portion 132 may form the sixth boundary surface 133B along the circumferential direction of the central axis of the mounting portion 132.

The fourth boundary surface 133A and the sixth boundary surface 133B may form a stepped portion. The second boundary surface 421 and the sixth boundary surface 133B may form an angle of about 90 degrees.

60 65 The fifth boundary surface 442C and the sixth boundary surface 133B may face each other in the radial direction of the pipe portion 441. The fifth boundary surface 442C and

the sixth boundary surface 133B may come into close contact with each other when the insertion portion 410 moves in a radial direction. Accordingly, the fifth boundary surface 442C and the sixth boundary surface 133B may block radial directional movement of the insertion portion 410 from the mounting portion 132.

A rear surface of the inlet 111 may form a seventh boundary surface 111A. The seventh boundary surface 111A may form a ring shape around a central axis of the inlet 111.

A front surface of the protrusion portion 442 may form an eighth boundary surface 442D. The eighth boundary surface 442D may form a ring shape around the central axis of the pipe portion 441. The eighth boundary surface 442D may be spaced apart from the seventh boundary surface 111A in the direction of the passage 401.

When the coupling part 440 is mounted in the outer surface of the insertion portion 410, the rear surface of the inlet 111 and the front surface of the protrusion portion 442 may face each other in the radial direction of the pipe portion 441. Accordingly, the seventh boundary surface 111A and the eighth boundary surface 442D may block movement of the main housing 110 and the first connection portion 420 in the direction of the passage 401.

The actions of the first to eighth boundary surfaces may be summarized as follows.

(1) The first boundary surface 442A and the second boundary surface 421 may enable relative rotation between the housing 100 and the connector 400 with the central axis of the insertion portion 410 as a center.

(2) The first boundary surface 442A and the second boundary surface 421 may block relative movement between the housing 100 and the connector 400 in the direction of the passage 401.

(3) The seventh boundary surface 111A and the eighth boundary surface 442D may block relative movement between the housing 100 and the connector 400 in the direction of the passage 401.

(4) The third boundary surface 442B and the fourth boundary surface 133A may block relative movement between the housing 100 and the connector 400 in the radial direction.

(5) The fifth boundary surface 442C and the sixth boundary surface 133B may block relative movement between the housing 100 and the connector 400 in the radial direction.

In some cases, when the first connection member rotates, friction may be focused on the contact surface between the first connection member and the second connection member. The focused friction may accelerate abrasion of components.

In some implementations, the relative rotation between the housing 100 and the connector 400 may be made by action no. (1). The relative movement between the housing 100 and the connector 400 in the direction of the passage 401 may be dually blocked by actions no. (2) and (3). The relative movement between the housing 100 and the connector 400 in the radial direction may be dually blocked by actions no. (4) and (5).

That is, when the first connection portion 420 rotates about the central axis of the insertion portion 410, friction may be dispersed between the first boundary surface 442A and the second boundary surface 421, between the third boundary surface 442B and the fourth boundary surface 133A, between the fifth boundary surface 442C and the sixth boundary surface 133B, and between the seventh boundary surface 111A and the eighth boundary surface 442D.

Accordingly, the vacuum cleaner 1 of the present disclosure has an advantage in that when the first connection

portion 420 rotates about the central axis of the insertion portion 410, the friction may not be focused on a specific area, which may prevent or reduce abrasion of components.

FIG. 11 is a partially exploded perspective view of the main housing 110 of FIG. 5 and a driver 200. FIG. 12 is an exploded perspective view of the driver 200 of FIG. 11. FIG. 13 is a side view of the driver 200 of FIG. 11.

The driver 200 may rotate the rotating brush 310. The driver 200 may be coupled to one side surface (hereinafter referred to as a "left side surface") of the main housing 110. As illustrated in FIG. 4, the side surface cover 150 may cover the driver 200. The side surface cover 150 may be coupled to a left side surface of the housing 100 by a locking structure such as a hook. In the side surface cover 150, a hole may be formed for inflow and outflow of air.

As illustrated in FIG. 11, the driver 200 may include a bracket 210, a motor 220, and a transmission 230.

The bracket 210 may be coupled to the main housing 110 by a bolt. The bracket 210 may block the left side surface of the main housing 110. In the left side surface of the main housing 110, a plurality of fastening portions (N) to which a bolt is screw-coupled may be formed. In the bracket 210, a plurality of insertion portions (T) to which a bolt is inserted may be formed.

The motor 220 may generate a rotational force. The motor 220 may be provided as a brushless direct current (BLDC) motor. The motor 220 may be coupled to the bracket 210. When the bracket 210 is coupled to the main housing 110, the motor 220 may be positioned behind the rotating brush 310. A rotational axis of the motor 220 may be aligned with a rotational axis of the rotating brush 310.

As illustrated in FIGS. 12 and 13, the transmission 230 may transfer rotational motion of the motor 220 to the rotating brush 310. The transmission 230 may be mounted in the bracket 210. The transmission 230 may include a first belt transmission 231 and a second belt transmission 232.

The first belt transmission 231 may transfer the rotational motion of the motor 220 to a middle pulley (R). When the bracket 210 is coupled to the main housing 110, the middle pulley (R) may be disposed between the motor 220 and the rotating brush 310. An axis of the middle pulley (R) may be aligned with the rotational axis of the rotating brush 310.

A fixing shaft (A) may be coupled to the bracket 210. The middle pulley (R) may be rotatably mounted in the fixing shaft (A) by a bearing (B). A groove may be formed in the fixing shaft (A). A snap ring (S) may be mounted in the groove to restrict deviation of the middle pulley (R).

The middle pulley (R) may include a first middle pulley 231B and a second middle pulley 232B. The first middle pulley 231B and the second middle pulley 232B may rotate simultaneously. The first middle pulley 231B and the second middle pulley 232B may be integrally produced.

On outer surfaces of the first middle pulley 231B and the second middle pulley 232B, equally-spaced grooves may be formed as in a gear. That is, on outer surfaces of the first middle pulley 231B and the second middle pulley 232B, teeth may be formed as in a gear. The number of teeth of the first middle pulley 231B may be greater than the number of the teeth of the second middle pulley 232B.

As illustrated in FIGS. 12 and 13, the first belt transmission 231 may include a driving pulley 231A, the first middle pulley 231B, and a first belt 231C.

The first belt transmission 231 may be spaced apart from the rotating brush 310. That is, the driving pulley 231A, the first middle pulley 231B, and the first belt 231C may be positioned in the opposite side to the rotating brush 310 with respect to the bracket 210.

The driving pulley 231A may be coupled to an axis of the motor 220. On an outer surface of the driving pulley 231A, teeth may be formed as in a gear. The number of teeth of the first middle pulley 231B may be greater than the number of the teeth of the driving pulley 231A.

The first belt 231C may be wound around the driving pulley 231A and the first middle pulley 231B. The first belt 231C may be wound around the driving pulley 231A and the first middle pulley 231B in the manner of an open belt. Accordingly, the first belt 231C may transfer rotational motion of the driving pulley 231A to the first middle pulley 231B in the same rotational direction.

The first belt 231C may be provided as a timing belt. Accordingly, the first belt 231C may accurately transfer the rotational motion of the driving pulley 231A to the first middle pulley 231B.

As described above, the number of the teeth of the first middle pulley 231B may be greater than the number of the teeth of the driving pulley 231A. Accordingly, a torque of the first middle pulley 231B may be greater than a torque of the driving pulley 231A. In addition, a rotation speed of the first middle pulley 231B may be slower than a rotation speed of the driving pulley 231A.

The second belt transmission 232 may transfer rotational motion of the middle pulley (R) to the rotating brush 310. The second belt transmission 232 may include a driven pulley 232A, the second middle pulley 232B, a second belt 232C, and a first shaft 232D. In some examples, the first shaft 232D may be referred to as a first shaft.

The second belt transmission 232 may be spaced apart from the rotating brush 310. That is, the driven pulley 232A, the second middle pulley 232B, and the second belt 232C may be positioned in the opposite side to the rotating brush 310 with respect to the bracket 210.

The first shaft 232D may be inserted into the rotating brush 310. The first shaft 232D may have a diameter in a range not exceeding a diameter of the rotating brush 310, regardless of the capacity of the motor 220.

The driven pulley 232A may be rotatably mounted in the bracket 210. A hole may be formed in the bracket 210. The bearing (B) may be mounted in the hole. A shaft of the driven pulley 232A may be rotatably coupled to the bearing (B). The shaft of the driven pulley 232A may pass through the bracket 210. The shaft of the driven pulley 232A may be aligned with the rotational axis of the rotating brush 310.

The first shaft 232D may transfer rotational motion of the driven pulley 232A to the rotating brush 310. At one end of the rotating brush 310, a second shaft 313 may be provided. In some examples, the second shaft may be referred to as a second shaft.

Hereinafter, for easy understanding of the present disclosure, the direction of a rotational axis of the rotating brush 310 will be referred to as an "axial direction." For example, the rotating brush 310 may extend along the axial direction.

The first shaft 232D may be inserted into the second shaft 313 to transfer rotational motion to the second shaft 313. A rotational axis of the first shaft 232D may be on the same line as that of the rotational axis of the rotating brush 310.

The first shaft 232D may be coupled to the shaft of the driven pulley 232A from the opposite side to the driven pulley 232A. When the bracket 210 is coupled to the main housing 110, the first shaft 232D may be disposed inside the main housing 110. As illustrated in FIG. 11, in the left side surface of the main housing 110, a hole 110H into which the first shaft 232D is inserted may be formed.

In some examples, the driving pulley 232A may include a gear or teeth disposed at an outer surface of the driven

pulley 232A. The number of teeth of the driven pulley 232A may be greater than the number of the teeth of the second middle pulley 232B.

The second belt 232C may be wound around the driven pulley 232A and the second middle pulley 232B. The second belt 232C may be wound around the driven pulley 232A and the second middle pulley 232B in the manner of an open belt.

The second belt 232C may transfer rotational motion of the second middle pulley 232B to the driven pulley 232A in the same rotational direction. Accordingly, a rotational direction of the motor 220 is the same as a rotational direction of the first shaft 232D.

The second belt 232C may be provided as a timing belt. Accordingly, the second belt 232C may accurately transfer rotational motion of the second middle pulley 232B to the driven pulley 232A.

As described above, the number of the teeth of the driven pulley 232A may be greater than the number of the teeth of the second middle pulley 232B. Accordingly, a torque of the driven pulley 232A may be greater than a torque of the second middle pulley 232B. In addition, a rotation speed of the driven pulley 232A may be smaller than a rotation speed of the second middle pulley 232B.

As a result, a rotation speed of the first shaft 232D may be slower than a rotation speed of the motor 220, and a torque of the first shaft 232D may be greater than a torque of the motor 220. The rotating brush 310 may rotate with relatively high torque, moving dust and debris on the floor to the suction space 101.

FIG. 14 is a bottom view of the suction nozzle 10 of FIG. 2. FIG. 15 is cross-sectional view of the suction nozzle 10 of FIG. 14 when the suction nozzle 10 is cut along the line from A to A'.

As illustrated in FIGS. 13 and 14, when the bracket 210 is coupled to the main housing 110, the motor 220 may be positioned behind the rotating brush 310. The rotational motion of the motor 220 may be transferred to the rotating brush 310, which is spaced apart from the motor 220, by the first belt transmission 231 and the second belt transmission 232.

The position of the middle pulley (R) may be determined depending on a distance between the motor 220 and the rotating brush 310. In addition, a length of the first belt 231C may be determined depending on a distance between the driving pulley 231A and the first middle pulley 231B and on diameters of the driving pulley 231A and the first middle pulley 231B. In addition, a length of the second belt 232C may be determined depending on a distance between the driven pulley 232A and the second middle pulley 232B and on diameters of the driven pulley 232A and the second middle pulley 232B.

Components of the vacuum cleaner 1 may have various specifications depending on the use of the vacuum cleaner 1. The capacity of the motor 220 and the diameter and the material of the rotating brush 310 may also be variously determined depending on the use of the vacuum cleaner 1.

For example, a vacuum cleaner for use in shops may include a motor with a greater capacity and a rotating brush with a greater diameter than those of a vacuum cleaner for use in a household. The material of the rotating brush may be determined from among metal and a synthetic resin depending on the use of the vacuum cleaner.

In some cases, a diameter of the rotating brush may be considered when the motor is selected. In some cases, the capacity of the motor may not be increased to a desired level.

In some implementations, as for the vacuum cleaner for use in a household, a relatively lower height of the suction nozzle may be more advantageous in terms of usability. This is because a relatively lower height of the suction nozzle enables easy access to spaces with a relatively low height.

In some cases, the diameter of the rotating brush may not be decreased to a desired level.

In some implementations, the driver 200 may be positioned outside the rotating brush 310. Accordingly, the present disclosure has an advantage in that the diameter of the rotating brush 310 may be determined regardless of the size and shape of the motor 220.

In addition, the present disclosure may have an advantage in that the capacity of the motor 220 may be determined regardless of the diameter of the rotating brush 310.

When the suction nozzle 10 is moved back and forth, inertia may act on the suction nozzle 10 in the movement direction. In some cases, a vacuum cleaner in related art may have a center of gravity of the suction nozzle focused on the front side of the suction nozzle. Accordingly, when the suction nozzle is moved forwards, the back of the suction nozzle may be lifted by the inertia.

In addition, when the suction nozzle is inclined forwards, friction between the rotating cleaning unit and the floor increases. Excessive friction between the rotating cleaning unit and the floor may damage the floor.

In some implementations, the driver 200 may be positioned behind the rotating brush 310. Accordingly, the center of gravity of the suction nozzle 10 of the present disclosure may be located further to the rear in comparison to the center of gravity of the suction nozzle of the vacuum cleaner in related art. Accordingly, in some implementations, there is a lesser likelihood of the suction nozzle 10 becoming inclined forwards while the suction nozzle 10 is moved back and forth.

When the suction nozzle 10 is relatively heavy, the usability of the vacuum cleaner 1 may decrease. In the case of an upright type vacuum cleaner, wheels and a rotating brush in a housing are rubbed against the floor. Thus, a physically weak user, such as an elderly person or a child, may not be able to smoothly move the upright type vacuum cleaner.

Accordingly, there is a need to reduce the weight of the suction nozzle of the upright type vacuum cleaner. However, for conventional vacuum cleaners, a two-stage planetary gear set composed of many parts is generally used.

In some implementations, the rotational motion of the motor 220 may be transferred to the rotating brush 310 by the first belt transmission 231 and the second belt transmission 232. A belt transmission transfers rotational motion through a simple pulley-belt structure. Accordingly, the transmission 230 may have advantages compared to the two-stage planetary gear set in that the number of parts and the weight of the transmission 230 significantly decrease.

As illustrated in FIG. 15, the mounting housing 130, along with the main housing 110, the lower housing 120, and the bracket 210, may form an isolated space 102. The isolated space 102 may be a space isolated from the suction space 101. The isolated space 102 may be positioned behind the rotating brush 310. The dust and debris in the suction space 101 may not be able to enter the isolated space 102.

When the bracket 210 is coupled to the main housing 110, the motor 220 may be provided in the isolated space 102. In addition, the first belt transmission 231 and the second belt transmission 232 may be isolated from the suction space 101 by the bracket 210. Accordingly, even when the driver 200

is not inserted into the rotating brush 310, contamination of the driver 200 caused by dust and debris may be prevented or reduced.

When the rotating brush 310 rubs the floor, the temperature of the rotating brush 310 may increase. In some cases, in related art, the motor and the gear unit may be positioned within the rotating brush. Accordingly, the vacuum cleaner of related art may have a limitation in that heat emission of the motor and the gear unit is relatively slow. Such an increase in the temperature of the motor and the gear unit directly leads to a decrease in performance and failure of the motor and gear unit.

In some implementations, the driver 200 may be spaced apart from the rotating brush 310. In particular, the motor 220, the pulleys, and the belts, which generate heat energy, may be positioned in the isolated space 102 isolated from the rotating brush 310. The vacuum cleaner 1 of the present disclosure has an advantage in that the heat energy of the motor 220, the pulleys, and the belts is quickly discharged through the bracket 210 and the housing 100.

FIG. 16 is a perspective view of the brush module 300 of FIG. 4. FIG. 17 is an exploded perspective view of the brush module 300 of FIG. 16. FIG. 18 is a perspective view of the suction nozzle 10 of FIG. 2 with the brush module 300 separated.

As illustrated in FIGS. 16 and 17, the brush module 300 may include the rotating brush 310 and the detachable cover 320.

The rotating brush 310 may push dust and debris on the floor to behind the rotating brush 310. The rotating brush 310 may include a body 311, a brush member 312, a second shaft 313, and a third shaft 314.

The body 311 may form the frame of the rotating brush 310. The body 311 may be formed in the shape of a hollow cylinder. A central axis of the body 311 may act as a central axis of the rotating brush 310. The body 311 may have a rotational inertia which is uniform along the circumferential direction thereof. The body 311 may be produced of a synthetic resin or metal.

The brush member 312 may be attached to an outer surface of the body 311. The brush member 312 may include a plurality of bristles. When the body 311 rotates, the plurality of bristles may lift dust and debris on the floor into the air. The plurality of bristles may include fiber bristles and metal bristles.

The fiber bristles and the metal bristles may be disposed randomly on the outer surface of the body 311. The fiber bristles and the metal bristles may be directly attached to the outer surface of the body 311. In some examples, a fiber layer may be attached to the outer surface of the body 311. Then, the fiber bristles and the metal bristles may be attached to the fiber layer.

The fiber bristles may be produced of a synthetic resin, such as nylon. The metal bristles may include a conductive material. The metal bristles may be produced by coating bristles made of a synthetic resin with a conductive material.

In some examples, static electricity generated in the fiber bristle may be discharged to the floor or removed through the metal bristle rather than being transferred to the user.

As illustrated in FIGS. 16 and 17, the second shaft 313 may receive rotational motion of the first shaft 232D. The second shaft 313 may be provided in an opening at one side of the body 311. The second shaft 313 may be inserted into the opening at one side of the body 311.

An insertion groove 313H may be formed on an outer surface of the second shaft 313. A protruding portion 311A may be formed along the length direction of an inner surface

of the body 311. When the second shaft 313 is inserted into the opening of the body 311, the protruding portion 311A may be inserted into the insertion groove 313H. The protruding portion 311A may block relative rotation of the second shaft 313.

In the second shaft 313, a space into which the first shaft 232D is inserted may be formed. When the rotating brush 310 moves in the axial direction thereof, the first shaft 232D may be inserted into the second shaft 313.

The first shaft 232D and the second shaft 313 may engage each other on a plurality of contact surfaces. When the first shaft 232D and the second shaft 313 engage each other, a rotational axis of the first shaft 232D and a rotational axis of the second shaft 313 may be on the same line.

Rotational motion of the first shaft 232D may be transferred to the second shaft 313 through the contact surfaces. With the first shaft 232D and the second shaft 313 engaging each other, the rotational axis of the rotating brush 310 and the rotational axis of the first shaft 232D may be on the same line.

As illustrated in FIGS. 16 and 17, the third shaft 314 may connect the body 311 to the detachable cover 320 in such a manner that the body 311 rotates. The third shaft 314 may be provided in an opening at the other side of the body 311. The third shaft 314 may be inserted into the opening at the other side of the body 311.

An insertion groove 314H may be formed on an outer surface of the third shaft 314. A protruding portion 311A may be formed along the length direction of the inner surface of the body 311. When the third shaft 314 is inserted into the opening of the body 311, the protruding portion 311A may be inserted into the insertion groove 314H. The protruding portion 311A may block relative rotation of the third shaft 314.

A bearing (B) may be mounted in the third shaft 314. A fixing shaft (A) may be provided in the detachable cover 320. The bearing (B) may support the fixing shaft (A) in such a manner that the fixing shaft (A) rotates. A groove may be formed in the fixing shaft (A). A snap ring (S) may be mounted in the groove to restrict separation of the third shaft 314 and the fixing shaft (A).

The detachable cover 320 may be rotated about the rotational axis of the rotating brush 310, to be detachably coupled to the housing 100.

FIG. 19 is a perspective view of the suction nozzle 10 of FIG. 2 with the housing 100 and the detachable cover 320 coupled. FIG. 20 is a perspective view of the suction nozzle 10 of FIG. 2 with the housing 100 and the detachable cover 320 decoupled.

Hereinafter, for easy understanding of the present disclosure, a state in which the detachable cover 320 is coupled to the housing 100 will be referred to as a "coupled state." In addition, a state in which the detachable cover 320 is decoupled from the housing 100 by rotating about the rotational axis of the rotating brush 310 will be referred to as a "decoupled state."

In the decoupled state of FIG. 20, when the detachable cover 320 is pulled in the axial direction, the brush module 300 may be separated from the housing 100 as in FIG. 18.

Hereinafter, for easy understanding of the present disclosure, a rotational direction in which the detachable cover 320 is coupled to the housing 100 will be referred to as a "first rotational direction." A rotational direction in which the detachable cover 320 is decoupled from the housing 100 will be referred to as a "second rotational direction."

In the decoupled state of FIG. 20, when the detachable cover 320 is rotated in the first rotational direction, the detachable cover 320 may be coupled to the housing 100 as in FIG. 19.

FIG. 21 is a perspective view of the suction nozzle 10 of FIG. 18 with the rotating brush 310 unillustrated. FIG. 22 is a perspective view of the suction nozzle 10 of FIG. 21 with the pressing button 141 separated. FIG. 23 is a perspective view of the detachable cover 320 of FIG. 21.

As illustrated in FIGS. 21 and 22, at one side surface (hereinafter referred to as a "right side surface") of the main housing 110, a guide rail 112, a plurality of first walls 112A, a plurality of second walls 112B, and a second protrusion 113.

The guide rail 112 may be formed on the right side surface of the main housing 110. The guide rail 112 may be formed in the circumferential direction of the rotational axis of the first shaft 232D.

An outer surface of the guide rail 112 may guide a rotation of first protrusions 324 about the rotational axis of the first shaft 232D. The first protrusions 324 may be guided to the outer surface of the guide rail 112 and rotate in the first rotational direction and the second rotational direction.

The first walls 112A may be formed on the outer surface of the guide rail 112. The first walls 112A may protrude from the outer surface of the guide rail 112. The first protrusions 324 may rotate in the first rotational direction to enter between the first walls 112A and the main housing 110. Here, the first walls 112A may block axial-directional movement of the first protrusions 324.

The second walls 112B may be formed on the outer surface of the guide rail 112. The second walls 112B may protrude from the outer surface of the guide rail 112. In the coupled state, the second walls 112B may block rotation of the first protrusions 324 in the first rotational direction.

The second protrusion 113 may be formed on the right side surface of the main housing 110. The second protrusion 113 may be formed on the right side surface of the main housing 110. In the detachable cover 320, a guide groove 325 may be formed along an approximately circumferential direction of the fixing shaft (A).

An inner surface of the guide groove 325 may guide a rotation of the second protrusion 113 about the rotational axis of the rotating brush 310. In the coupled state and the decoupled state, the second protrusion 113 may be maintained in a state of being inserted into the guide groove 325.

As illustrated in FIGS. 21 and 22, the pressing button 141 may be mounted in the support housing 140. The pressing button 141 may selectively block rotation of the detachable cover 320. The pressing button 141 may include a button portion 141A, an elastic member 141B, a first blocking portion 141C, and a second blocking portion 141D.

The button portion 141A may form a surface that the user pushes on. A first mounting groove 141H1 into which the button portion 141A is inserted may be formed in the support housing 140.

A pair of shaft portions 141E may be formed in the button portion 141A. The pair of shaft portions 141E may be formed on both side surfaces of the button portion 141A. A pair of shaft grooves 141H4 may be formed on an inner surface of the first mounting groove 141H1. The pair of shaft grooves 141H4 may be formed on inner side surfaces of the first mounting groove 141H1 at both sides thereof.

The shaft portions 141E may be inserted into the shaft grooves 141H4. The button portion 141A may be rotated about the shaft portions 141E inserted into the shaft grooves 141H4.

The first blocking portion 141C may extend from the button portion 141A. In the coupled state, the first blocking portion 141C may block rotation of a third protrusion 326.

A second mounting groove 141H2 may be formed in the support housing 140. A part of the first blocking portion 141C may be inserted into the second mounting groove 141H2. The first blocking portion 141C may be rotated within the second mounting groove 141H2 about the shaft portions 141E.

When the user pushes the button portion 141A, the pressing button 141 may be rotated about the shaft portions 141E. Here, the first blocking portion 141C may deviate from a rotational route of the third protrusion 326.

The elastic member 141B may be interposed between the button portion 141A and the housing 100. The elastic member 141B may form a force that pushes the button portion 141A outwards between the shaft portions 141E and the first blocking portion 141C.

Accordingly, when an external force applied to the button portion 141A is removed, the first blocking portion 141C may return to the rotational route of the third protrusion 326. In the support housing 140, a third mounting groove 141H3 into which the elastic member 141B is inserted may be formed.

The second blocking portion 141D may extend from the button portion 141A. In the coupled state, the second blocking portion 141D may block axial-directional movement of a fourth protrusion 327. In the coupled state, the axial-directional movement of the fourth protrusion 327 may be blocked by the second blocking portion 141D.

The detachable cover 320 may rotatably support the rotating brush 310. The detachable cover 320 may be rotated about the rotational axis of the rotating brush 310 to be detachably coupled to the housing 100.

As illustrated in FIGS. 21 and 23, the detachable cover 320 may include a cover body 321, a hub 322, a protruding rib 323, a first protrusion 324, a third protrusion 326, and a fourth protrusion 327.

In the coupled state, the cover body 321 may cover a right side surface of the housing 100. A hole may be formed in the cover body 321 for inflow and outflow of air.

An edge portion of the cover body 321 may have an outline that is similar to the profile of the right side surface of the housing 100. The edge portion of the cover body 321 may protrude towards an edge of the right side surface of the housing 100. In the coupled state, the edge portion of the cover body 321 may come into close contact with the edge of the right side surface of the housing 100.

The hub 322 may be a portion to which the fixing shaft (A) is coupled. The fixing shaft (A) may be inserted into a mold when the detachable cover 320 is injection-molded. The hub 322 may be formed on an inner surface of the detachable cover 320. Here, the inner surface of the detachable cover 320 may be a surface that faces the housing 100.

The protruding rib 323 may be a portion that allows the first protrusion 324 to be spaced apart from the inner surface of the detachable cover 320 by a certain distance. The protruding rib 323 may be formed on the inner surface of the detachable cover 320. The protruding rib 323 may be formed in a circumferential direction of the hub 322.

A plurality of first protrusions 324 may be formed in the protruding rib 323. The first protrusions 324 may protrude from the protruding rib 323 towards the hub 322. The first protrusions 324 may be spaced apart from each other in a circumferential direction of the fixing shaft (A).

The first protrusions 324 may be spaced apart from the inner surface of the detachable cover 320 by a certain

distance by the protruding rib 323. The first protrusions 324 may be guided to the outer surface of the guide rail 112 and rotate in the first rotational direction and the second rotational direction.

5 The third protrusion 326 may be formed on an edge of the inner surface of the detachable cover 320. When the detachable cover 320 is detachably coupled to the housing 100, the third protrusion 326 may be caught by the first blocking portion 141C. The third protrusion 326 may be spaced farther apart from the fixing shaft (A), compared to the first protrusion 324.

10 The third protrusion 326, along with an inclined surface 326A, may form a catching surface 326B. When the detachable cover 320 is rotated about the fixing shaft (A), the first 15 blocking portion 141C may interfere with rotation of third protrusion 326.

When the detachable cover 320 is rotated in the first rotational direction, the inclined surface 326A may form a gentle inclination which pushes the first blocking portion 141C towards the central axis of the rotating brush 310. The first blocking portion 141C may be pushed only towards the central axis. Accordingly, when the detachable cover 320 is rotated in the first rotational direction, the first blocking portion 141C may be pushed by the catching surface 326B.

20 When the detachable cover 320 is rotated in the second rotational direction in the coupled state, the catching surface 326B may form a surface that pushes the first blocking portion 141C in a direction that is approximately perpendicular to the central axis. The first blocking portion 141C 25 may be pushed only towards the central axis. Accordingly, when the detachable cover 320 is rotated in the second rotational direction in the coupled state, the first blocking portion 141C may not be pushed.

30 In order to rotate the detachable cover 320 in the second rotational direction in the coupled state, the user should push the pressing button 141 in such a manner that the first blocking portion 141C deviates from the rotational route of the third protrusion 326.

35 A fourth protrusion 327 may be formed on an edge of the inner surface of the detachable cover 320. The fourth protrusion 327 may be positioned further forward in the first rotational direction than the third protrusion 326. In the coupled state, axial-directional movement of the fourth protrusion 327 may be blocked by the second blocking portion 141D. In the coupled state, a rotation of the fourth protrusion 327 in the first rotational direction may be 40 blocked by the support housing 140.

45 FIG. 24 is a side view of the suction nozzle 10 of FIG. 20. FIG. 25 is a side view of the suction nozzle 10 of FIG. 19 with the pressing button 141 pressed. FIG. 26 is a side view of the suction nozzle 10 of FIG. 19.

The process of mounting the brush module 300 in the housing 100 is as follows.

50 First, move the brush module 300 in the axial direction to insert the first shaft 232D into the second shaft 313. When the first shaft 232D is inserted into the second shaft 313, the detachable cover 320 may be in a state of being decoupled from the housing 100, that is, in the decoupled state described in detail above.

55 60 As illustrated in FIG. 24, in the decoupled state, the protruding rib 323 may surround the guide rail 112. In the decoupled state, the second protrusion 113 may be inserted into the guide groove 325.

65 Thereafter, the user may rotate the detachable cover 320 in the first rotational direction. Then, the first protrusions 324 may be guided to the outer surface of the guide rail 112 to rotate in the first rotational direction. The second protrusion

sion 113 may move inside the guide groove 325 with the rotational axis of the rotating brush 310 as a center.

As illustrated in FIG. 25, in the process in which the detachable cover 320 is rotated in the first rotational direction, the third protrusion 326 may get the first blocking portion 141C to deviate from the rotational route through the inclined surface 326A, and then the third protrusion 326 may keep rotating in the first rotational direction.

As illustrated in FIG. 26, when the fourth protrusion 327 is blocked by the support housing 140, the rotation of the detachable cover 320 in the first rotational direction may be completed. In this state, the detachable cover 320 may be in a state of being coupled to the housing 100, that is, in the coupled state described in detail above.

In the coupled state, the third protrusion 326 may be blocked by the first blocking portion 141C, which blocks a rotation of the third protrusion 326 in the second rotational direction. In the coupled state, axial-directional movement of the fourth protrusion 327 may be blocked by the second blocking portion 141D.

Here, the first walls 112A may block axial-directional movement of the first protrusions 324. The second walls 112B may block rotation of the first protrusions 324 in the first rotational direction.

The process of separating the brush module 300 from the housing 100 is as follows.

As illustrated in FIG. 25, the user may firstly press the pressing button 141. When the user presses the pressing button 141, the first blocking portion 141C may deviate from the rotational route of the third protrusion 326.

Here, the user may rotate the detachable cover 320 in the second rotational direction. Then, the third protrusion 326 may rotate in the second rotational direction about the fixing shaft (A) to be spaced apart from the first blocking portion 141C.

The second protrusion 113 may move inside the guide groove 325 with the rotational axis of the rotating brush 310 as a center.

As illustrated in FIG. 24, the first protrusions 324 may be guided to the outer surface of the guide rail 112 to rotate in the second rotational direction. The first protrusions 324 may rotate in the second rotational direction to deviate from between the main housing 110 and the first walls 112A. In this state, the detachable cover 320 may be in a state of being decoupled from the housing 100, that is, in the decoupled state described in detail above.

In some cases of a vacuum cleaner in related art, a coupling force between the side surface cover and the main body is generated by a locking structure such as a hook. Such a coupling structure as a locking structure is a relatively simple structure. However, in a locking structure, when the direction of the suction nozzle is changed, it is difficult to stably support an axial-directional force applied to a rotating cleaning unit.

In some implementations, when the detachable cover 320 is rotated in the second rotational direction while pressing the pressing button 141, the housing 100 and the detachable cover 320 may be easily decoupled. In addition, in the decoupled state, when the detachable cover 320 is rotated in the first rotational direction, a coupling force may be generated between the housing 100 and the detachable cover 320.

Furthermore, in the coupled state, the first walls 112A may block the axial-directional movement of the first protrusions 324. The first walls 112A may be spaced apart from each other in the circumferential direction of the fixing shaft (A).

The first walls 112A, disposed along the circumferential direction of the fixing shaft (A), may disperse and support the axial-directional force that is applied to the rotating brush 310 when the direction of the suction nozzle 10 is changed.

The axial-directional movement of the fourth protrusion 327 may be blocked by the second blocking portion 141D. In addition, in the coupled state, the second walls 112B may block rotation of the first protrusions 324 in the first rotational direction.

The third protrusion 326 may be blocked by the first blocking portion 141C, which blocks a rotation of the third protrusion 326 in the second rotational direction. The rotation of the fourth protrusion 327 may be blocked by the support housing 140, which blocks a rotation of the fourth protrusion 327 in the first rotational direction.

That is, without pressing the pressing button 141, the detachable cover 320 may not be moved in the axial direction or rotated about the fixing shaft (A). The vacuum cleaner 1 of the present disclosure may form a strong coupling structure in which the housing 100 and the detachable cover 320 may not easily be decoupled by an external force without pressing the pressing button 141.

FIG. 27 is a perspective view of the brush module 300 and the driver 200 of the suction nozzle 10 of FIG. 19. FIG. 28 is a side view of the driver 200 of FIG. 27. FIG. 29 is a perspective view of the first shaft 232D of FIG. 28.

Hereinafter, for easy understanding of the present disclosure, an axial direction in which the rotating brush 310 moves so that the first shaft 232D is inserted into the second shaft 313 will be referred to as a “first axial direction.” In addition, the opposite direction to the first axial direction will be referred to as a “second axial direction.”

The first shaft 232D may transfer rotational motion to the second shaft 313. In the second shaft 313, a space into which the first shaft 232D is inserted may be formed.

When the rotating brush 310 moves in the first axial direction, the first shaft 232D may be inserted into the second shaft 313. When the first shaft 232D is inserted into the second shaft 313, the first shaft 232D and the second shaft 313 may engage each other to come into contact with each other on a plurality of contact surfaces.

Rotational motion of the first shaft 232D may be transferred to the second shaft 313 through the contact surfaces. With the first shaft 232D and the second shaft 313 engaging each other, a rotational axis of the rotating brush 310 and a rotational axis of the first shaft 232D may be on the same line.

In some cases, a driver in related art may be coupled to the rotating cleaning unit within the rotating cleaning unit by the fixing member. Accordingly, it may be difficult to disassemble and reassemble the driver and the rotating cleaning unit in the vacuum cleaner in related art.

In some implementations, when the detachable cover 320 is rotated while pressing the pressing button 141 for the decoupled state, the engagement between the first shaft 232D and the second shaft 313 may be released. Accordingly, the user may easily decouple the rotating brush 310 and the driver 200 of the vacuum cleaner 1 of the present disclosure.

As illustrated in FIGS. 28 and 29, the first shaft 232D may include a hub 232DA and a plurality of first transfer portions 232DB.

The hub 232DA may be a portion to which a shaft of the driven pulley 232A (hereinafter referred to as a “pulley shaft”) is coupled. The first shaft 232D may rotate about the hub 232DA.

The first transfer portions 232DB may be axisymmetric with each other about the pulley shaft (PA). The number of the first transfer portions 232DB may be variously determined. For example, the number of the first transfer portions 232DB may be four.

A single first transfer portion 232DB may form three surfaces. A single first transfer portion 232DB may form a first surface 232D1, a third surface 232D2, and a fifth surface 232D3.

First surfaces 232D1 of the first transfer portions 232DB may extend from a side surface of the hub 232DA in an approximately radial direction of the pulley shaft (PA). The first surfaces 232D1 of the first transfer portions 232DB may be surfaces that transfer the rotational motion of the first shaft 232D to the second shaft 313. The first surfaces 232D1 may form a relatively small angle with a radial direction of the pulley shaft (PA).

The first surfaces 232D1 may form a spiral around the pulley shaft (PA). The first surfaces 232D1 may be positioned along the rotational direction of the first shaft 232D towards the first axial direction. The first surfaces 232D1 may be axisymmetric with each other about the hub 232DA. For example, the first surfaces 232D1 may be curved along the rotational direction of the first shaft 232D.

The surface area of the first surfaces 232D1 may increasingly decrease towards the second axial direction. The first surfaces 232D1 may be positioned increasingly closer to the rotational axis of the rotating brush 310 towards the second axial direction.

Third surfaces 232D2 of the first transfer portions 232DB may extend from a side surface of the hub 232DA in an approximately radial direction of the pulley shaft (PA). The third surfaces 232D2 may form a relatively small angle with the radial direction of the pulley shaft (PA).

The third surfaces 232D2 may be surfaces that receive a rotational inertia of the rotating brush 310. Rotational inertia refers to the property by which a rotating object maintains its state of uniform rotational motion.

The second shaft 313 may receive the rotational force of the motor 220 through the first shaft 232D. However, if a rotation speed of the second shaft 313 is greater than a rotation speed of the first shaft 232D, the rotational inertia of the rotating brush 310 may be transferred to the first shaft 232D.

That is, after an operation of the driver 200 stops, the rotational inertia of the rotating brush 310 may be transferred to the first shaft 232D through the second shaft 313 until the rotation of the rotating brush 310 stops.

Alternatively, if the rotation speed of the rotating brush 310 is adjusted, the rotational inertia of the rotating brush 310 may be transferred to the first shaft 232D through the second shaft 313 in the process where a rotation speed of the motor 220 decreases.

The third surfaces 232D2 may form a plane aligned with the axial direction of the rotating brush 310. The third surfaces 232D2 may be axisymmetric with each other about the pulley shaft (PA).

The surface area of the third surfaces 232D2 may increasingly decrease towards the second axial direction. The third surfaces 232D2 may be positioned increasingly closer to the rotational axis of the rotating brush 310 towards the second axial direction.

When the first shaft 232D is inserted into the second shaft 313, a single second transfer portion 313B may be inserted between a first surface 232D1 and a third surface 232D2 that are adjacent to each other.

The fifth surface 232D3 may be a surface connecting the first surface 232D1 and the third surface 232D2. The fifth surface 232D3 may connect the first surface 232D1 and the third surface 232D2 in a circumferential direction of the pulley shaft (PA). Fifth surfaces 232D3 of the first transfer portions 232DB may be axisymmetric with each other about the pulley shaft (PA).

The surface area of the fifth surfaces 232D3 may increasingly decrease towards the second axial direction. The fifth surfaces 232D3 may be positioned increasingly closer to the rotational axis of the rotating brush 310 towards the second axial direction.

FIG. 30 is a side view of the brush module 300 of FIG. 27. FIG. 31 is a partial perspective view of the second shaft 313 of FIG. 30.

As illustrated in FIGS. 30 and 31, the second shaft 313 may include a shaft body 313A and a plurality of second transfer portions 313B.

The shaft body 313A may be inserted into an opening at one side of the body 311. An insertion groove 313H may be formed on an outer surface of the shaft body 313A. A protruding portion 311A may be formed along the length direction of an inner surface of the body 311.

When the shaft body 313A is inserted into the opening of the body 311, the protruding portion 311A may be inserted into the insertion groove 313H. The protruding portion 311A may block relative rotation of the shaft body 313A.

The second transfer portions 313B may be axisymmetric with each other about the pulley shaft (PA). When the first shaft 232D is inserted into the second shaft 313, the first shaft 232D and the second shaft 313 may engage each other to come into contact with each other on a plurality of contact surfaces. Accordingly, the number of the second transfer portions 313B may be equal to the number of the first transfer portions 232DB.

A single second transfer portion 313B may form three surfaces. A single second transfer portion 313B may form a second surface 313B1, a fourth surface 313B2, and a seventh surface 313B3. The shaft body 313A may form a sixth surface 313A1.

Second surfaces 313B1 of the second transfer portions 313B may extend from an inner surface of the shaft body 313A in an approximately radial direction of the pulley shaft (PA). The second surfaces 313B1 may form a relatively small angle with the radial direction of the pulley shaft (PA).

The second surfaces 313B1 may form a spiral around the pulley shaft (PA). The second surfaces 313B1 may be positioned along the rotational direction of the first shaft 232D towards the first axial direction.

The second surfaces 313B1 may be axisymmetric with each other about the shaft body 313A. The second surfaces 313B1 may be positioned increasingly closer to the rotational axis of the rotating brush 310 towards the second axial direction.

FIG. 32 is a cross-sectional view of the suction nozzle 10 of FIG. 19. FIG. 33 is a cross-sectional view of the suction nozzle 10 of FIG. 32 when the suction nozzle 10 is cut along the line from B to B'. FIG. 34 is a cross-sectional view of the suction nozzle 10 of FIG. 32 when the suction nozzle 10 is cut along the line from C to C'. FIG. 35 is a cross-sectional view of the suction nozzle 10 of FIG. 32 when the suction nozzle 10 is cut along the line from D to D'.

The second surfaces 313B1 may be surfaces receiving the rotational force of the first shaft 232D. When the first shaft 232D is inserted into the second shaft 313, the second surfaces 313B1 and the first surfaces 232D1 may form first contact surfaces in a spiral shape along the axial direction.

On the first contact surfaces formed in the spiral shape, the rotational force of the first shaft 232D may be transferred to the second shaft 313.

The first contact surfaces may be axisymmetric with each other about the rotational axis of the rotating brush 310. The first contact surfaces may be positioned along the rotational direction of the first shaft 232D towards the first axial direction.

FIG. 36 is a drawing illustrating a force acting on a first contact surface (C1). FIG. 37 is a drawing illustrating a force acting on the second surface 313B1.

A rotational force (F) of the first shaft 232D that is applied to the second surface 313B1 through the first contact surface (C1) may be divided into a force (F2; hereinafter referred to as a "friction component force") in parallel with the first contact surface (C1) and a force (F1; hereinafter referred to as an "action force") in the normal direction of the first contact surface (C1).

The first surface 232D1 and the second surface 313B1 may be smooth surfaces. That is, the frictional coefficient of the first contact surface (C1) may be relatively very small.

In some examples, the friction component force (F2) may be relatively small compared to the action force (F1). Accordingly, the first surfaces 232D1 and the second surfaces 313B1 may slip on the first contact surfaces (C1) due to the rotational force of the first shaft 232D.

In some examples, the action force (F1) may act on the second surface 313B1 through the first contact surface (C1). An action force (F1') that is transferred to the second surface 313B1 through the first contact surface (C1) may be divided into an axial-directional component force (F1x'; hereinafter referred to as a "movement component force") and a component force in the same direction as the rotational force of the first shaft 232D (F1y'; hereinafter referred to as a "rotation component force").

The rotating brush 310 may be rotated by the rotation component force (F1y'). In addition, the rotating brush 310 may be pushed in the second axial direction by the movement component force (F1x'). The ratio of the movement component force (F1x') to the rotation component force (F1y') varies depending on a lead of the first contact surface (C1). The lead of the first contact surface (C1) may be equal to a lead of the first surface 232D1 and the second surface 313B1.

In some cases, a vacuum cleaner in related art may include a rotating cleaning unit that moves in the axial direction thereof due to the reaction force and the friction force of the floor. The axial-directional movement of the rotating cleaning unit may cause noise on contact surfaces between the rotating cleaning unit and the rotating support unit and among the first side surface cover and the second side surface cover and the chamber. In addition, the axial-directional movement of the rotating cleaning unit may cause damage to the coupling structure of the first side surface cover, the second side surface cover, and the chamber.

In some implementations, the vacuum cleaner 1 may have an advantage in that as the rotating brush 310 is continuously pushed in the second axial direction by the movement component force (F1x'), axial-directional movement of the rotating brush 310 may be restricted even when the reaction force and the friction force of the floor are applied in the axial direction.

A surface area of the first surfaces 232D1 may increasingly decrease towards the second axial direction. Accordingly, a surface area of the first contact surface may increasingly decrease towards the second axial direction.

The first surfaces 232D1 and the second surfaces 313B1 may be positioned increasingly closer to the rotational axis of the rotating brush 310 towards the second axial direction. Accordingly, the first contact surfaces may be positioned increasingly closer to the rotational axis of the rotating brush 310 towards the second axial direction.

Thus, as a distance by which the rotating brush 310 is pushed in the second axial direction increases, the movement component force (F1x') that is transferred to the second surfaces 313B1 through the first contact surface (C1) may decrease. Accordingly, a phenomenon in which the rotating brush 310 is excessively pushed in the second axial direction by the movement component force (F1x') may be restricted.

Fourth surfaces 313B2 of the second transfer portions 313B may extend from a side surface of the shaft body 313A in an approximately radial direction of the pulley shaft (PA). The fourth surfaces 313B2 may form a relatively small angle with the radial direction of the pulley shaft (PA).

The fourth surfaces 313B2 may be axisymmetric with each other about the pulley shaft (PA). The fourth surfaces 313B2 may be positioned increasingly closer to the rotational axis of the rotating brush 310 towards the second axial direction.

The fourth surfaces 313B2 may form a plane aligned with the axial direction of the rotating brush 310. When the first shaft 232D pushes the second shaft 313 in the second axial direction on the first contact surfaces formed in the spiral shape, the first shaft 232D and the second shaft 313 may be spaced apart in the axial direction while maintaining the first contact surfaces.

The first surfaces 232D1 and the second surfaces 313B1 may be positioned along the rotational direction of the first shaft 232D towards the first axial direction. That is, with a single first transfer portion 232DB as a center, the first surface 232D1 and the third surface 232D2 may get closer to each other towards the second axial direction.

In addition, with a single second transfer portion 313B as a center, the second surface 313B1 and the fourth surface 313B2 may get closer to each other towards the second axial direction.

Accordingly, when the first shaft 232D pushes the second shaft 313 in the second axial direction through the first contact surface, the third surface 232D2 and the fourth surface 313B2 may be spaced apart from each other. That is, when the first shaft 232D pushes the second shaft 313 in the second axial direction through the first contact surface, the fourth surfaces and the third surfaces may not come into contact with each other on the second contact surfaces.

The fourth surfaces 313B2 may be surfaces which transfer the rotational inertia of the rotating brush 310 to the first shaft 232D. When the first shaft 232D is inserted into the second shaft 313, the fourth surfaces and the third surfaces 232D2 may form a plurality of second contact surfaces aligned with the axial direction. The second contact surfaces may be axisymmetric with each other about the rotational axis of the rotating brush 310.

FIG. 38 is a drawing illustrating a force acting on a second contact surface (C2).

After an operation of the driver 200 stops, the rotational inertia (Fi) of the rotating brush 310 may be transferred to the first shaft 232D through the second contact surfaces (C2) until rotation of the rotating brush 310 stops. Alternatively, while a rotational speed of the motor 220 decreases, the rotational inertia (Fi) of the rotating brush 310 may be transferred to the first shaft 232D through the second contact surfaces C2.

The rotational inertia (Fi) of the rotating brush 310 may be transferred to the first shaft 232D until the second shaft 313 rotates at the same speed as that of the first shaft 232D or stops. A rotational force of the second shaft 313 that is applied to the third surface 232D2 through the second contact surface (C2) may act on the third surface 232D2 in a perpendicular direction. 5

Accordingly, until the second shaft 313 rotates at the same speed as that of the first shaft 232D or stops, the first shaft 232D and the second shaft 313 may stably maintain the 10 second contact surface.

Thus, relative movement of the first shaft 232D and the second shaft 313, which is caused by an external force transferred in the radial direction of the pulley shaft PA in the process in which the rotational speed of the motor 220 15 decreases, may be minimized.

When the first shaft 232D is inserted into the second shaft 313, the sixth surface 313A1 and the fifth surfaces 232D3 may form a contact surface. The sixth surface 313A1 and the fifth surface 232D3 may act as a boundary surface for 20 blocking relative movement of the first shaft 232D and the second shaft 313 caused by an external force transferred in the radial direction of the pulley shaft (PA).

The seventh surface 313B3 may be a surface connecting the second surface 313B1 and the fourth surface 313B2. The 25 seventh surface 313B3 may connect the second surface 313B1 and the fourth surface 313B2 in a circumferential direction of the pulley shaft (PA). Seventh surfaces 313B3 of the second transfer portions 313B may be axisymmetric with each other about the pulley shaft (PA).

The seventh surfaces 313B3 may be positioned increasingly closer to the rotational axis of the rotating brush 310 towards the second axial direction. When all the contact surfaces between the first shaft 232D and the second shaft 313 come into close contact with each other, the first shaft 232D may be inserted into the second shaft 313. With the first shaft 232D being inserted into the second shaft 313, the 35 seventh surfaces 313B3 may be spaced apart from the hub 232DA.

While the foregoing has been given by way of illustrative example of the present disclosure, all such and other modifications and variations thereto as would be apparent to those skilled in the art are deemed to fall within the broad scope and ambit of this disclosure as is herein set forth. Accordingly, such modifications or variations are not to be regarded as a departure from the spirit or scope of the present disclosure, and it is intended that the present disclosure cover the modifications and variations of this disclosure provided they come within the scope of the appended claims and their equivalents. 40

In the vacuum cleaner of the present disclosure, the first shaft and the second shaft come into contact with each other on a plurality of contact surfaces that form a spiral around the axis of the rotating brush, such that the rotational force of the first shaft is used to rotate the rotating brush and push the rotating brush in the axial direction. Accordingly, even when a reaction force and a friction force of the floor are applied to the rotating brush, axial-directional movement of the rotating brush may be minimized. In this regard, the vacuum cleaner of the present disclosure overcomes the limitations of existing technology, and there is thus sufficient possibility not only of the use of the related technology but also of the actual sale of apparatuses to which the related technology is applied. In addition, the present disclosure can be obviously and practically implemented by those skilled in the art. Therefore, the present disclosure is industrially applicable. 45

What is claimed is:

1. A vacuum cleaner comprising:
a main body configured to generate a differential air pressure with respect to an outside of the vacuum cleaner; and

a suction nozzle configured to suction dust from the outside based on the differential air pressure, the suction nozzle comprising:

a housing that defines an inlet configured to receive the dust,

a first shaft disposed at a side of the housing,
a driver disposed at the housing and configured to rotate the first shaft,

a rotating brush that extends along an axis and is configured to, based on rotation of the first shaft, rotate about the axis to thereby move the dust on a surface to toward the inlet,

a detachable cover configured to rotatably support a first end of the rotating brush, and

a second shaft disposed at a second end of the rotating brush and configured to engage with the first shaft to rotate the rotating brush,

wherein the first shaft and the second shaft are configured to come into contact with each other and to define a plurality of first contact surfaces having a spiral shape about the axis of the rotating brush, the first contact surfaces being configured to transfer a rotational force from the first shaft to the second shaft,

wherein the first contact surfaces extend toward the axis of the rotating brush as the first shaft extends in an axial direction from the second end of the rotating brush toward the first end of the rotating brush, the first contact surfaces protruding from an end of the first shaft facing the driver,

wherein a surface area of the first contact surfaces decreases as the first shaft extends in the axial direction, wherein the first shaft and the second shaft are configured to further define a plurality of second contact surfaces that extend parallel to the axis of the rotating brush and protrude from the end of the first shaft facing the driver, and

wherein each of the first contact surfaces extends from one of the second contact surfaces toward another of the second contact surfaces to thereby define the spiral shape about the axis of the rotating brush.

2. The vacuum cleaner of claim 1, wherein the second contact surfaces are configured to transfer a rotational inertia of the rotating brush to the first shaft based on an operation of the driver being stopped or a rotation speed of the rotating brush being changed, and

wherein a surface area of the second contact surfaces decreases as the first shaft extends in the axial direction.

3. The vacuum cleaner of claim 2, wherein the second contact surfaces are axisymmetric with respect to the axis of the rotating brush.

4. The vacuum cleaner of claim 1, wherein the first contact surfaces are axisymmetric with respect to the axis of the rotating brush.

5. The vacuum cleaner of claim 4, wherein the first contact surfaces are curved along a rotational direction of the first shaft and extend in a direction from the second end of the rotating brush toward the first end of the rotating brush.

6. The vacuum cleaner of claim 5, wherein the first shaft and the second shaft are configured to contact each other at the first contact surfaces and slide with respect to each other,

31

and wherein the first shaft is configured to push the second shaft in the axial direction through the first contact surfaces.

7. The vacuum cleaner of claim 6,

wherein the first shaft and the second shaft are configured to, based on the first shaft pushing the second shaft in the axial direction of the rotating brush, be separated from the second contact surfaces.

8. The vacuum cleaner of claim 1, wherein the first shaft comprises a plurality of first transfer portions configured to insert into the second end of the rotating brush, and

wherein the second shaft comprises a plurality of second transfer portions that are configured to come into contact with the first transfer portions to thereby define the plurality of first contact surfaces.

9. The vacuum cleaner of claim 1, wherein the housing defines a side hole configured to receive the first shaft.

10. The vacuum cleaner of claim 9, wherein the second shaft is disposed in a through-hole of the rotating brush and defines an aperture that is configured to receive the first shaft passing through the side hole of the housing.

11. The vacuum cleaner of claim 1, further comprising a third shaft inserted into the first end of the rotating brush, wherein the detachable cover is configured to cover the third shaft.

12. A vacuum cleaner comprising:

a main body configured to generate a differential air pressure with respect to an outside of the vacuum cleaner; and

a suction nozzle configured to suction dust from the outside based on the differential air pressure, the suction nozzle comprising:

a housing that defines an inlet configured to receive the dust,

a first shaft disposed at a side of the housing, the first shaft comprising a plurality of first surfaces,

a driver disposed at the housing and configured to rotate the first shaft,

a rotating brush that extends along an axis and is configured to, based on rotation of the first shaft, rotate about the axis to thereby move the dust on a surface toward the inlet,

a detachable cover configured to rotatably support a first end of the rotating brush, and

a second shaft disposed at a second end of the rotating brush and configured to engage with the first shaft to rotate the rotating brush, the second shaft comprising a plurality of second surfaces configured to come into contact with the first surfaces to thereby define a plurality of first contact surfaces,

wherein the plurality of first contact surfaces have a spiral shape about the axis of the rotating brush and are configured to transfer a rotational force from the first shaft to the second shaft,

wherein the first contact surfaces extend toward the axis of the rotating brush as the first shaft extends in an axial direction from the second end of the rotating brush toward the first end of the rotating brush, the first contact surfaces protruding from an end of the first shaft facing the driver,

wherein a surface area of the first contact surfaces decreases as the first shaft extends in the direction from the second end of the rotating brush toward the first end of the rotating brush,

32

wherein the first shaft and the second shaft are configured to further define a plurality of second contact surfaces that extend parallel to the axis of the rotating brush and protrude from the end of the first shaft facing the driver, and

wherein each of the first contact surfaces extends from one of the second contact surfaces toward another of the second contact surfaces to thereby define the spiral shape about the axis of the rotating brush.

13. The vacuum cleaner of claim 12, wherein the first shaft further comprises a plurality of third surfaces,

wherein the second shaft further comprises a plurality of fourth surfaces that are configured to come into contact with the third surfaces to thereby define the plurality of second contact surfaces,

wherein the second contact surfaces are configured to transfer a rotational inertia of the rotating brush to the first shaft based on an operation of the driver being stopped or a rotation speed of the rotating brush being changed, and

wherein a surface area of the second contact surfaces decreases as the first shaft extends in the axial direction.

14. The vacuum cleaner of claim 13, wherein the first contact surfaces are curved along a rotational direction of the first shaft and extend in a direction from the second end of the rotating brush to the first end of the rotating brush,

wherein one of the first surfaces and one of the second surfaces are configured to slide with respect to each other based on the rotational force being applied from the first shaft to the second shaft, and wherein the first shaft is configured to push the second shaft in the axial direction.

15. The vacuum cleaner of claim 12, wherein the first shaft further comprises a plurality of third surfaces,

wherein the second shaft further comprises a plurality of fourth surfaces that are configured to come into contact with the third surfaces to thereby define the plurality of second contact surfaces, and

wherein one of the third surfaces and one of the fourth surfaces are configured to, based on the first shaft pushing the second shaft in the axial direction, be spaced apart from each other.

16. The vacuum cleaner of claim 12, wherein the first shaft comprises a plurality of first transfer portions that define the first surfaces, respectively, the first transfer portions being configured to insert into the second end of the rotating brush, and

wherein the second shaft comprises a plurality of second transfer portions that define the second surfaces, respectively, the second transfer portions being configured to come into contact with the first transfer portions to thereby define the plurality of first contact surfaces.

17. The vacuum cleaner of claim 12, wherein the housing defines a side hole configured to receive the first shaft.

18. The vacuum cleaner of claim 17, wherein the second shaft is disposed in a through-hole of the rotating brush and defines an aperture that is configured to receive the first shaft passing through the side hole of the housing.
